UNITED STATES PATENT OFFICE.

EMIL A. HIRNER, OF ALLENTOWN, PENNSYLVANIA.

MECHANISM FOR OPERATING SPECIAL NEEDLES IN KNITTING-MACHINES.

No. 860,868.

Specification of Letters Patent.

Patented July 23, 1907.

Application filed July 5, 1901. Serial No. 67,113.

To all whom it may concern:

Be it known that I, EMIL A. HIRNER, a citizen of the United States, residing at Allentown, in the county of Lehigh and State of Pennsylvania, have invented certain new and useful Mechanism for Operating Special Needles in Knitting-Machines, whereof the following is a specification, reference being had to the accompanying drawings.

In many varieties of knitting it is necessary to cause certain of the needles to perform different movements and, therefore, different operations from the others. Usually these needles are called upon to produce a special form of stitch, while the others continue to produce plain knitting, and I will therefore distinguish them from the other needles by using the phrase "special needles". They may be interspersed among the others singly or by groups. The operations which they may perform are various. For example, in the production of vertically striped, patterned or figured knitting, it often occurs that certain needles must produce at intervals in the fabric tuck stitches, draw stitches, drop stitches, or the like.

Various methods have been devised for effecting the temporary separation of the special needles from the others, such, for example, as causing the butts of the special needles to differ in length from the butts of the rest of the needles. Likewise, various means have been proposed for controlling the distinct operation of these needles during that portion of their course when they operate differently from the others.

My present invention relates to certain novel mechanism whereby I accomplish the separation and the separate operation of the special needles by very simple means.

My invention also relates to the use and arrangement of the paired knitting cams of a stocking knitter in connection with the separation and the separate operation of the special needles.

My invention also relates to the operation of the special needles to produce open work in hosiery, or other vertical stripes, with provision of means whereby the open work or other stripe may be succeeded by plain knitting at any point of the knitting, as for example in knitting the back of the leg of a stocking with open work or stripes, while the heel, sole and toe are of plain knitting, as shown in my Patent No. 699,954, dated May 15th, 1902.

In the accompanying drawings, Figure 1, is a plan view of the knitting and cam cylinders of an ordinary stocking knitter, embodying my invention. Figs. 2, and 3, are side elevations, respectively, of a plain and special needle. Fig. 4, is an alternative way of forming the butt of the special needle. Fig. 5, is a partial horizontal section of a cam cylinder showing, *in situ*, the switch-cam and special draw-down cam. Fig. 6,

is an elevational view of these cams. Fig. 7, is an enlargement of the vertical section 7, 7, Fig. 5, with the hooked butt of a special needle in engagement with the cams. Fig. 8, is a similar enlargement of the vertical section 8, 8, Fig. 5. Fig. 9, is a similar enlargement of the vertical section 9, 9, Fig. 5, viewed in the opposite direction. Fig. 10, is a diagrammatic view of the interior of a cam cylinder extended in a plane, with the successive positions of both classes of needles, as they come under the influence of the cams, indicated thereon, the cams and needles being arranged in this case for the production of a longitudinal open work stripe. Fig. 11, is a similar diagram with the cams arranged for the production of a draw or tuck stitch at certain intervals. Fig. 12, is a partial horizontal section of a cam cylinder fitted with a modified form of switch cam employed in conjunction with the special needle of Fig. 4. Fig. 13, is a diagrammatic interior view. Fig. 14, is an enlarged elevational view of the same. Fig. 15, is a plan view of the essential parts of a stocking knitter (the needle cylinder being omitted), showing the relation of the parts employed in my invention to the ordinary parts of such a knitting machine. Fig. 16, is a partial sectional view along the line 16, 16, Fig. 15, showing the construction of the jack cam.

Referring to the stocking knitter shown in Fig. 15, it will be observed that the cam cylinder is connected by bevel gearing with a shaft by which it may be either rotated or reciprocated. I have shown a handle whereby this may be accomplished manually, but it is preferably accomplished by any of the known mechanisms provided in automatic stocking knitters. The cam cylinder is fitted with a thread carrier, Q, and on its interior with needle grooves, within which is interposed a set of reciprocatory knitting cams, as will be hereafter more particularly described. The needle cylinder is fitted with ordinary latch needles, consisting of plain needles, among which special needles may be interspersed.

The plain needles are of the ordinary construction shown in Fig. 2. The special needles shown in Fig. 3, differ from these plain needles in that the part below the butt, and also part of the lower side of the butt itself, is cut or broken away, leaving the butt to terminate in the form of a curved hook. I will now describe the mechanism employed by me to separate or divert these special needles, which during part of their course run in the ordinary cam groove with the ordinary needles, from this cam groove into their special groove, premising that this mechanism is capable of much variation in detail, depending upon the particular sort of knitting machine to which the invention is applied.

A cam plate A, is placed on the inside of the cam

cylinder after the manner of ordinary knitting cams, at the point where it is desired that the course of the special needles shall deviate from the ordinary cam groove, the upper edge of this cam plate being arranged 5 to form part of the lower side of this groove. The upper and operative surface of this cam plate consists of three portions, (see Fig. 6), a slight rise a , a level a' , and a long descent a'' . Along the top of this cam plate, chiefly coincident with the level a' , is cut 10 a horizontal channel or groove b , which occupies only that side of the plate which is farthest from the needle cylinder, and therefore adjacent to the wall of the cam cylinder, (which for convenience may be termed the outer side of the plate), and which nowhere breaks 15 the inner wall of the cam plate. The inner edge of this channel is deflected across to the outer side of the plate, thus forming a cam incline b' , which differs from all the ordinary needle cams of a knitting machine in that it exerts its force along the line of a radius 20 of the knitting cylinders. Opposite the cam incline, b' , the wall of the cam cylinder has a corresponding horizontal groove b'' , cut in it.

Outside of cam plate A, there is inserted in the wall of the cam cylinder a cam plate C, which I term 25 a special draw-down cam. Its shape will be best understood from its illustration in Figs. 5 to 9. Its inner surface has an inclined channel c , cut into it, corresponding in position to the descent a'' , of cam plate A, and so arranged in reference to it that the 30 descent a'' , comes opposite about the median line of the channel c . The upper edge of this channel forms a cam incline c' , which partially overhangs the upper edge of cam plate A, as seen in Figs. 5, and 7.

The operation of the mechanism thus described is 35 as follows:—The line or circle of the butts of the needles, consisting of plain needles having interspersed among them special needles with hooked butts (Fig. 3), run along the cam groove of the cam cylinder until they reach the rise a , of the switch cam. Ordinarily, 40 it is true, the needles are supported fixedly in the machine and it is the cam groove which rotates in the opposite direction but it is much more convenient to consider only the relative motion of these parts, and to think of the cam cylinder as stationary and 45 the needle butts as running in the groove, and I will consequently employ this phraseology. When the butts of the plain needles reach the cam plate A, they ride up the rise a , to the level a' , and then pass on without further interference, for the special draw- 50 down cam C, does not project far enough to reach or affect them, as will be best seen by observing their relative positions in Fig. 1. When the butts of the special needles reach the switch cam, the downwardly projecting hook at the end of the butt enters the chan- 55 nel b , whereupon the flat or cut edge of this hook is immediately brought into contact with cam incline b' , so that the needle, instead of being elevated by rise a , is drawn out radially a short distance, against the tension of the needle band into the position first 60 of Fig. 8, and then of Fig. 7, the end of the butt being thus gradually drawn into the channel c , of cam plate C. As soon as the upper edge of the butt comes into 65 contact with the overhanging cam incline c' , it is compelled to ride down it, disengagement of the butt from the channel c , being in the meantime prevented

by the upper edge of the descent a'' , of cam plate, A, which projects part way over the channel. The special needle is therefore not free to disengage this cam and to return to its normal seat in the needle cylinder until it has reached the lower end of the cam incline c' , by which it has in the meantime been depressed a corresponding distance. The separation or sorting of plain from special needles thus effected may then be taken advantage of to further deflect by other cams these needles from each other and to cause them to go through such separate operations as may be desired. 70

As has been already stated, much variation in the details of the construction of this cam may occur without departing from the principle of operation which I have explained. Thus, for example, it is plain that the hook of the butt instead of being turned down as in Fig. 3, may be turned up, as in Fig. 4. In this case the arrangement of the cam inclines will differ, and may be as shown in Figs. 12, 13, and 14, in which the switch 80 cam T, is furnished with a descent v , the level v' , the second descent v'' , and the deflected channel t , by which the butts of the special needles are drawn out radially and depressed to the extent of the second descent v'' , while the ordinary needles pass the cam 90 with only the slight depression of the descent v .

Having thus described the separation of the special from the plain needles, I will now describe how such or other known sorting mechanism may be rendered useful in stocking knitters of the ordinary construction, 95 for the purpose of producing different kinds of striped, patterned or figured knitting, with little change or rearrangement of the ordinary knitting cams found in these machines. For this purpose I will first describe the application of my switch cam to an ordinary stocking knitter for the purpose of producing a stocking having open work stripes down the back as well as the front of the leg. Such a stocking I have described in United States Letters Patent No. 699,954, granted to me under date of May 13th, 1902. I have also therein 100 described the method of knitting employed in making it in so far as it is independent of the mechanism for actuating the needles. It is this latter mechanism which I will now proceed to describe, with the explanation that the special needles which are employed 105 to form the open work stripe down the back of the leg of the stocking, and which may be situated at any desired intervals among the plain needles, must, after having been advanced sufficiently to throw the loop which each carries below the latch, be caused to shed the loop 110 before it can advance to take new thread. In this way they are prevented from knitting, although they take thread along with the rest of the needles and draw out as much as would be required to form a stitch. 115

Referring now to Fig. 10, A, is the return or end cam 120 of the construction already described. It will be observed that it is in the position of the ordinary left-hand end cam of the knitter and that its cam surface a'' , serves the function of such a cam. B, is a guard cam opposing the level a' , of the cam A. It may also be 125 conveniently used, as a pull down cam to lower the needles after knitting a heel or toe pocket, when controlled by proper mechanism. C, is the special draw-down cam, which I have already described to be employed with my hooked butt special needles, and which 130

differs from the rest of the cam plates in being placed at a greater radial distance from the axis of the knitting cylinder than the rest, so that it operates only upon the butts of the special needles. D, and E, are respectively the left and right stitch cams of the ordinary construction used in stocking knitters. F, and G, are respectively left and right guard cams. H, is the top center cam and I, the bottom center cam, both situated between the stitch cams. O, is a right hand end cam, J, and K, are, for the purposes of the present description, only guard cams, although they may conveniently be used in conjunction with other mechanism, at the commencement of the formation of the heel and toe pockets, as needle raising cams. L, is a special shedding cam for which M, is the corresponding depressing cam. N, is a special jack cam, which must be provided with mechanism, either manual or automatic, whereby at the proper point in the operation of the machine it may be raised or lowered, it being in action when raised and out action when lowered. As shown in Fig. 16, the operation of this jack cam is effected manually, by means of the spring pressed pin n. The means for narrowing and widening the back of the tube for the formation of the heel and toe pockets in the stocking may be of the type patented by me in my Patent of March 22nd, 1892, No. 471,220, or of any other known type of automatic picker mechanism. The dotted lines z, z, z', z'; indicate the positions of openings in the cam cylinder through which may operate the automatic picker mechanism such as that shown in said patent.

For the purpose of producing the leg of a stocking with an open work stripe down the back, the cams should be arranged as shown in Fig. 10, with jack cam N, depressed and out of action. At intervals corresponding to the position of the stripes to be produced, special needles s, such as I have shown in Fig. 3, are inserted in the cam cylinder, five such needles being shown in the drawings. For the purpose of producing open work stripes down the front of the leg of the stocking, where the open work is continuous, the mere omission of needles is sufficient, and I have consequently indicated such omissions in that part of the needle cylinder which is to knit the front of the stocking, but this forms no part of my present invention.

The plain needles which perform only ordinary knitting pursue, during the rotation of the cam cylinder for the formation of the leg of a stocking, the ordinary knitting path, their motions being indicated by the line of the tops of the needles as seen in Fig. 10. The rise a, which corresponds to the similarly lettered rise of cam plate A, has no significance in the knitting operation. A further rise d, is effected by the upper surface of the left-hand stitch cam D, whereby the needles receive their full advance preparatory to taking thread for a new loop. The descent of the needles along h, and e, is accomplished by center cam H, and right-hand stitch cam E, the reception of thread occurring during the descent e. At the bottom of this descent, the latch of the needle is closed over the new thread and the old loop is shed over the hook of the needle. Thereupon the needles rise along o, under the influence of the right-hand return or end cam E, to the normal level, the new loop being still held upon the latch of the needle. Under the influence of cams L, and M, a tempo-

rary rise l, and descent m, is accomplished, whereby the loop is thrown below the latch of the needle, whereupon the operation begins to repeat itself.

The operation of the special needles, where they deviate from the rest, is indicated by the dotted line y, y, and is as follows: Instead of the rise a, these needles are drawn down by cams C, and D, as indicated at c, d'; at the bottom of the descent d', the loop which they carry is shed, thereupon, under the influence of the bottom center-cam I, they accomplish the rise i. It will be seen that the top of cam I, is reduced more than is usually the case. This is in order that its height may be accurately adjusted to deliver the special needles in among the line e, of the descending plain needles just above the point where thread is fed, in order that these needles may take thread with the rest, which they do, thereby immediately pulling out a sufficient amount of thread to make a loop, which loop, however, as has been explained, they shed before again taking thread.

85

The switch cam continues in operation during the entire knitting of the leg. When the heel is about to be knit, it is necessary that the special needles shall cease to operate as such, but shall move as do the plain needles, so as to change the open work at the back of the tube to plain knitting. This is accomplished by raising the jack cam N, by means of which all of the needles, special and plain are sufficiently raised before they meet the cam plate A, to clear the rise a, of the cam, so that thereafter the hooks of the special needles do not fall into the groove b, and are not drawn out into contact with the cam C. By again lowering the jack cam, at the proper point, the cam A, may be again caused to resume its function of sorting the special needles from the plain needles. In this way the jack cam 100 N, controls the operation of the sorting mechanism, so that the separation of the needles for the formation of open work may be caused to begin and end as desired during the knitting of a stocking. It is a peculiarity of the switch mechanism which I have just described 105 that even though, as a result of these transition movements, some of the butts of the special needles be left in an intermediate position (i. e. so that they will meet the rise a, part way up), there can be no uncertainty in the operation of the switch and no jamming of the 110 needle butts. The upper edge of the cam incline b', is slightly curved off, (as seen in Fig. 8), so that any butt, no matter what its position may have been as it approached rise a, is either held by incline b', and drawn under cam C, or else has slipped off the switch 115 cam and is entirely out of reach of cam C, before the cam is reached.

For the formation of the heel and toe pockets it is necessary that the cam cylinder should be reciprocated instead of rotated, and the automatic pickers put in action. It will be noticed that when the cam cylinder moves to the right the left-hand stitch cam D, is the operative knitting cam, and the cam plate A, serves its usual function as the end cam which advances the needles after they have shed their loops. It will therefore be seen that in the arrangement thus described, instead of inserting a special groove, into the cam cylinder for the purpose of imparting the necessary special motion to the special needles, I am able to employ in connection with their operation the groove under the 130

stitch cams, the ordinary needles passing over the leading stitch cam in the usual way, while the special needles are diverted into the groove below the following stitch cam without passing over or being advanced by 5 the leading stitch cam.

I will next describe the application of my invention to an ordinary stocking knitter for the purpose of producing a stocking with a figured effect, such as may be produced by the use of various special stitches, at 10 proper intervals. Such a stocking for example, I have described in United States Letters Patent No. 698,499, granted to me under date of April 29th, 1902. For the purpose of producing such a fabric or stocking, it is necessary that at proper intervals around the knitting 15 cylinder there be special needles which are capable of making tuck stitches, or other special stitches, instead of the ordinary stitches, and it is also necessary that the operation of these special needles shall be so controlled that in regular alternation, they shall operate specially 20 for a predetermined number of courses (usually not more than three or four at a time), and then for a predetermined number of succeeding courses proceed to knit as do the plain needles.

Referring now to Fig. 11, I have there shown the 25 method of arrangement of the cams of an ordinary stocking knitter with the insertion of my switch cam suitable for the production of a figured stocking of this sort. It will be observed that there are 18 special needles *s*, at intervals around the needle cylinder. It will also be 30 observe that the arrangement of the cams is in all respects identical with that of Fig. 10, previously described, except that cams *L*, and *M*, are entirely omitted, and that the bottom center cam *I*, is of a different shape. As shown, this cam *I*, is of the ordinary shape 35 for plain knitting, instead of having its upper edge reduced, as in Fig. 10; but it may be omitted altogether. The former alternative is resorted to when a tuck stitch is to be produced, and the latter when a draw stitch. The reason for the omission of shedding cam, 40 *L*, and its counterpart *M*, is that in this instance the loops upon the special needles must not be thrown below the latch prior to the operation of the stitch cam. As far as the movements of the plain needles are concerned, they are the same as before and need not be described, except that the throwing of the loop below the 45 needle latch does not here occur until the needle is advanced by the upper surface of the leading stitch cam. The special needles, under the control of the cam plate *A*, and the special draw-down cam *C*, with the loop 50 still within the latch, pass down below the stitch cam *D*, where, by reason of the loop being within the latch, instead of shedding it, they simply retain it. If, now, a tuck stitch is to be produced, the cam *I*, is used. The needle with its loop thereupon advances along the 55 ascent *i*, and is by it returned into line with its fellows before thread is fed into them, so that it receives new thread with the rest, the only difference being that not having shed its loop, each special needle now carries two threads instead of one within its hook. If the tuck 60 is to occupy three or four courses this operation continues during as many rotations of the machine, until three or four threads have thus been laid within the hook of the special needle. Thereupon, jack cam *N*, must be raised, (and if a specially figured pattern is to 65 be thus produced the operation of this cam will be

placed under the control of suitable automatic mechanism). By raising this cam the special needles are thrown above the line of the influence of the separating means so that during the next course they knit as do the others with the result that on reaching the rise *d*, they 70

throw all of the loops which they carry below their latch and then after receiving a new loop, shed all the old loops at once forming the ordinary tuck stitch. Where, instead of a tuck stitch, a draw stitch is to be produced, with the variation of the stitch which has 75 been referred to in the application last mentioned, cam *I*, is altogether omitted. The result is that the special needles depressed by cam *C*, and still holding a loop within their hooks, remain depressed, their butts pursuing the path of dotted line *i*, (Fig. 11), until after the 80 new thread has been fed between the adjacent plain needles. As a result this latter thread is laid across the space occupied by the special needles, which, on reaching the end cam *O*, are raised to the normal level still carrying the loop first mentioned, so that the succeeding 85 thread is shed across the space which they occupy without being knit. As long as the jack cam *M*, is depressed, this continues. When at the end of a predetermined number of courses, the stitch operating jack cam *N*, is again raised, the special needles take their place 90 in the operation with the plain needles, so that the new thread, instead of being interknit by the special needles with the loops of the course immediately preceding, is by them interlooped with that course, separate from it, it may be, by an interval of several courses, 95 which was the last course of plain knitting before the special needles were caused to operate specially.

It will be observed that in all of the forms of my invention which I have described a means for separating or sorting the needles is employed in connection with the ordinary paired stitch cams of a stocking knitter, and in such relation to them that the separation occurs as they reach the leading stitch cam over which some of the needles pass while others do not. This part of my invention is independent of the nature of those 105 needles, or the means employed for effecting their initial separation. For this reason the phrase "special needles" as it occurs in the claims is to be construed as designating needles which perform special functions in the knitting, and not as designating any special construction of the needle itself. By thus placing a sorting means at the point where the needles reach the leading stitch cam, whereby some of the needles are advanced over this cam to take thread, while others are not so advanced, it is obvious that it is possible to produce a great variety of striped or figured hosiery; and this is accomplished without interference with the reciprocal action of the knitting cams or otherwise complicating the mechanism which must be compressed within the limited cam groove of a stocking 110 knitter. And by means of the jack cam *N*, or similar, mechanism the control of the sorting mechanism as to when its operation is to begin or end is complete. Obviously in the knitting of hosiery it is usually necessary that any striped effect should cease during the reciprocal action of the machine for the production of the heel and toe pockets, and this is readily accomplished by this cam.

To simplify the phraseology of the claims, I will in those which have reference to the particular form of 130

sorting mechanism which I have described, speak of the needles, as moved either "radially" or "axially". By radial motion of the needles I mean a motion of translation towards or away from the axis of the needle cylinders, or, in the case of a flat machine, motion in the plane at right angles to the plane of the needle bed. By axial motion of the needles I mean their advancement or retraction along the line of their length, as in the ordinary knitting process. I will also employ in certain of the claims the phrase "a set of reciprocatory knitting cams". By this phrase I mean to include the essential elements of the paired cams, commonly employed in machines for knitting stockings where the cam cylinder is to be reciprocated for the production of the heel and toe pockets, consisting of symmetrically arranged and oppositely inclined depressing cams for forming the stitch, and symmetrically arranged and oppositely inclined advancing cams for advancing the needles preparatory to forming the stitch, and a feed arranged in such relation to the depressing cams as to coöperate with the one or the other of them according to the direction in which reciprocation occurs. Where such a set of cams, as for example those illustrated in the drawings, and above described, are employed, in conjunction with separating or sorting means in the lead of one of the advancing cams, some of the needles are advanced over the leading stitch cam to take thread or for other purposes, while others are withheld from said advance and are otherwise led into the groove below the following stitch cam.

Having thus described my invention, I claim:

1. In a knitting machine, the switch mechanism for special needles, which consists in the combination of special needles having hooked butts; a switch cam provided with a cam incline which engages the hooked butts and moves the special needles radially; and another cam incline, which moves them axially, substantially as described.
2. In a knitting machine, the switch mechanism for special needles, which consists in the combination of special needles having hooked butts; a switch cam provided with a horizontal cam incline which engages only the hooked butts; and a vertical cam incline within reach only of the needles which have engaged the horizontal cam incline, substantially as described.
3. In a knitting machine, the switch mechanism for special needles, which consists in the combination of special needles having hooked butts which run in the cam groove; a switch cam set in the cam groove having an inclined channel cut along the edge which opposes the hook of the butts, whereby the needles with hooked butts are moved radially; and another cam incline, within reach only of the needles which have been thus radially moved by the action of the inclined channel upon their hooked butts, which moves these needles axially, substantially as described.
4. In a knitting machine, the switch mechanism for special needles, which consists in the combination of special needles having downwardly hooked butts which run in the cam groove; a switch cam set in the lower side of the cam groove having an inclined channel cut along its upper edge, whereby the needles with hooked butts are moved radially; and another cam incline, within reach only of the needles which have been thus radially moved by the action of the inclined channel upon their hooked butts, which depresses these needles axially, substantially as described.
5. In a knitting machine, the switch mechanism for special needles, which consists in the combination of special needles having hooked butts which run in the cam groove; a switch cam set in the cam groove having an inclined channel cut along the edge which opposes the hook of the butts, whereby the needles with hooked butts are moved radially; another cam incline, within reach only of the needles which have been thus radially moved by the action

of the inclined channel upon their hooked butts, which moves these needles axially; and a movable jack cam on the side of the cam groove which opposes the hook of the butts, the advancement of which throws the hooked needle butts out of reach of the inclined channel, substantially as described.

6. In a circular knitting machine, the combination of a needle cylinder fitted with both plain and special needles; a cam cylinder fitted with a set of reciprocatory knitting cams; means to rotate and to reciprocate said cylinder; and a switch cam whereby the plain needles are passed into the set of knitting cams in the usual manner, over the leading and below the following stitch cams, while the special needles are led to the groove below the following stitch cam without being advanced by the leading stitch cam, substantially as described.

7. In a circular knitting machine the combination of a needle cylinder fitted with both plain and special needles; a cam cylinder fitted with a set of reciprocatory knitting cams; means to rotate and to reciprocate said cylinder; means situated beyond the following stitch cam, whereby the loops are thrown below the needle latches; and means situated in advance of the leading stitch cam, whereby the plain needles are caused to pass above the leading stitch cam, while the special needles are led to the groove below the following stitch cam without being advanced by the leading stitch cam, substantially as described.

8. In a circular knitting machine, the combination of a needle cylinder fitted with both plain and special needles; a cam cylinder fitted with a set of reciprocatory knitting cams; means to rotate and to reciprocate said cylinder; needle sorting means separating the plain from the special needles placed in advance of the reciprocatory knitting cams; and a movable cam whereby both the plain and the special needles may be prevented from coming under the influence of the sorting means, substantially as described.

9. In a circular knitting machine, the combination of a needle cylinder fitted with a set of reciprocatory knitting cams; means to rotate and to reciprocate said cylinder; needle sorting means placed in advance of the leading stitch cam, whereby the plain needles are allowed to pass above this stitch cam and the special needles deflected below it; and a bottom center cam partially cut away at its top, whereby the needles thus deflected are delivered in the groove below the following stitch cam just above the point where thread is fed, substantially as described.

10. In a circular knitting machine, the combination of a needle cylinder; a cam cylinder fitted with a set of reciprocatory knitting cams; means to rotate and to reciprocate said cylinder, whereby the needles are passed over the leading and below the following stitch cam for the production of the plain knitting stitch; and means whereby the special needles are led to the groove below the following stitch cam without being advanced by the leading stitch cam, for the production of vertical stripes, substantially as described.

11. In a circular knitting machine, the combination of a needle cylinder fitted with both plain and special needles; a cam cylinder fitted with a set of reciprocatory knitting cams; means to rotate and to reciprocate said cylinder; and a switch cam whereby, the plain needles are passed into the set of knitting cams in the usual manner over the leading and below the following stitch cams, while the special needles are deflected into the groove, below the leading stitch cam, which when the cam cylinder is reciprocated in the opposite direction, is used for the production of the knitting stitch, substantially as described.

12. In a stocking knitter, the combination of the needles and the knitting cylinders; a set of reciprocatory knitting cams including paired stitch cams in the cam cylinder; means whereby certain needles are caused to pass over the leading stitch cam and below the following stitch cam; and means whereby other needles are passed to the following stitch cam in position to receive yarn as they are depressed thereby but without passing over the leading stitch cam.

13. In a stocking knitter the cam cylinder of which is fitted with reciprocatory knitting cams, means whereby certain needles are caused to pass over the leading stitch cam and below the following stitch cam in the usual way; and means whereby the rest of the needles are led to the

groove below the following stitch cam without passing over the leading stitch cam.

14. In a stocking knitter provided with reciprocating knitting cams, means whereby certain of the needles are advanced by the leading stitch cam in the usual way; means whereby the rest of the needles are led into the groove below the following stitch cam without such advance; and means whereby all of the needles may when desired be caused to pass over the leading stitch cam and below the following stitch cam in the usual way.

15. In a circular knitting machine having independent needles, a cam cylinder having cams to coöperate with all of said needles to produce tubular work and to coöperate with each needle of a continuous portion of said needles

15 to form narrowed and widened fabric, and means to operate certain needles of said portion without causing them to knit, thereby forming drop work.

16. In a circular knitting machine having independent needles, and means for narrowing and widening the back of the knit tube, means for knitting open work and plain knitting at any point around said tube and means for changing the open work on the back of the tube to plain knitting.

17. In a circular knitting machine having independent needles, cam mechanism to coöperate with all of said needles, to produce tubular work, to coöperate with each needle of a continuous portion of said needles to form narrowed and widened fabric, and to operate certain needles of said portion without causing them to knit, thereby forming drop stitch work.
